UNITED STATES PATENT OFFICE.

CARL C. VENEMAN, OF CHICAGO, ILLINOIS, ASSIGNOR TO VAN SICKLEN CORPORATION, OF ELGIN, ILLINOIS, A CORPORATION OF DELAWARE.

DESIGN FOR A BADGE OR SIMILAR ARTICLE.

Application filed March 10, 1928. Serial No. 25,793. Term of patent 3½ years.

To all whom it may concern:

Be it known that I, CARL C. VENEMAN, a citizen of the United States, residing at Chicago, in the county of Cook and State of Illinois, have invented a new, original, and ornamental Design for a Badge or Similar Article, of which the following is a specification, reference being made to the accompanying drawing, forming a part thereof.

In the drawing, Fig. 1 is a front elevation of the badge or similar article showing my new design; and

Fig. 2 is an edge view or side elevation of the same.

I claim:—

The ornamental design for a badge or similar article, as shown.

Chicago, Illinois, March 8, 1928.

CARL C. VENEMAN.
